H. BARKER

AIR VALVE FOR INTERNAL COMBUSTION ENGINES

Filed Aug. 30, 1922

Henry Barker, Inventor

By Attorney

UNITED STATES PATENT OFFICE.

HENRY BARKER, OF BIRKENHEAD, ENGLAND, ASSIGNOR OF ONE-THIRD TO THOMAS BARKER AND ALONZA D. BERGEN, BOTH OF SAVANNAH, GEORGIA.

AIR VALVE FOR INTERNAL-COMBUSTION ENGINES.

Application filed August 30, 1922. Serial No. 585,270.

To all whom it may concern:

Be it known that I, HENRY BARKER, a subject of the King of Great Britain and Ireland, residing at Higher Tranmere, Birkenhead, Cheshire, England, have invented certain new and useful Improvements in Air Valves for Internal-Combustion Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a new or improved valve for automatically supplying extra air to internal combustion engines and has for its primary objects the economy of fuel and improving the running of the engine. It has been shown by a considerable number of tests on the road with various road vehicles propelled by internal combustion engines and using petrol as a fuel that the device effects an increase of about 25% of milage per gallon of fuel besides improving the running of the engine at all speeds.

The present invention relates to that type of ball valve for admitting auxiliary air to internal combustion engines in which a valve body adapted to be attached to the induction pipe or manifold is provided with an air inlet and outlet for admitting and discharging atmospheric air. The ball valve is controlled by a spiral compression spring which is regulated by a member screwing into the casing to press the ball on its seating and is provided with means for locking the regulating member when adjusted.

The present invention which obviates certain defects in practice with valves of the above type comprises a cylindrical body part formed with a cover at its lower end which is drilled with a series of holes for the admission of air, a coned valve seating of an appreciable depth carried within the cylindrical body part at some distance above the lower end thereof, a ball valve contacting with said seating of such a diameter that its lower portion projects beneath its seating, an internal screw thread formed in the upper portion of the valve body, and externally screw threaded plug screwing into said valve body and axially bored with

two diameters, a reduced part or spigot on the upper end of said plug adapted to screw into the induction pipe or manifold, means for allowing the plug to be adjusted with respect to the valve body, a lock nut engaging both the screwed plug and the upper end of the valve body and a spiral compression spring acting between the ball valve and the shoulder formed in the interior of the plug by the differing internal diameters thereof.

This invention will be now more particularly described making reference to the accompanying drawing in which—

Figure 1 is a view in side elevation of an extra air valve embodying the present invention.

Figure 2 is a view in plan thereof.

Figure 3 is a view in longitudinal section, and

Figure 4 is an underside plan view.

Throughout the views similar parts are marked with like letters of reference.

A cylinder *a* has its lower end closed by a plate or formed with a cover *a*¹ in which is drilled a series of holes *a*² for the admission of air. At some distance above the perforations or holes *a*² is fixed or formed a coned seating *a*³ of an appreciable depth for a ball valve *b* which is of such a diameter that it projects beneath the seating, as shown. The upper portion of the cylinder *a* is internally screw threaded to receive an externally screw threaded plug *c* which is formed at its upper end with a reduced part or spigot *c*¹.

This spigot *c*¹ is externally screw threaded adapting it to be screwed into the induction pipe or manifold of the engine. The plug *c* is bored with two diameters *c*², *c*³ through its length to form a passage for the air to the induction pipe or manifold. The shoulder formed between the bore *c*² and the bore *c*³ forms a bearing for the upper end of a helical spring *d*, the lower end of which impinges on the ball *b*. By screwing the plug, by means of flats *c*⁴ thereon, into or out of the cylinder *a*, provision is made for varying or adjusting the strength of the spring *d*. A lock nut *e* is provided on the plug *c* to engage the upper edge of the cylinder *a* to lock the plug in position after adjustment. The lower edge of the cylinder *a* may be provided with a hexagonal or a knurled head or flange *a*⁴ adapting the fit.

ting to be screwed into the induction pipe or manifold.

In some cases wire gauze may be placed over the perforations or holes a^2 to prevent entry of foreign matter with the sucked in air.

Having now particularly described and ascertained the nature of my said invention and in what manner the same is to be performed, I declare that what I claim is:—

An air supply valve for internal combustion engines, comprising a hollow valve-body portion formed with an internal valve-seat spaced a distance from the adjacent end 15 of the body portion, a closure-cap extending

partially up into the space beneath the valve seat and formed with borings to form in conjunction with the space between the cap and valve-seat an air cushion for the valve, a ball-valve resting on the valve seat and 20 projecting through the seat into the space between it and the closure-cap, an adjustable plug fitted in the upper portion of the valve-body and axially bored with two diameters, and a compression spring fitting 25 in the larger diameter bore of the plug and bearing against the ball-valve.

In testimony whereof I affix my signature.

HENRY BARKER.
